(57) **CLAIM**

The ornamental design for a water balloon with filling device, as shown and described.

DESCRIPTION

FIG. 1 is a front, top perspective view of a first embodiment of a water balloon with filling device, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1;

FIG. 10 is a front, top perspective view of a second embodiment of the water balloon with filling device;

FIG. 11 is a rear, bottom perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is an enlarged view of detail "18" identified in FIG. 10.

The dashed lines immediately adjacent the shaded surfaces depict the bounds of the claimed design whereas all other dashed lines in the figures illustrate portions of the water balloon with filling device that form no part of the claimed design. The dash dot dash lines in FIGS. 1, 9, 10 and 18 are for the purpose of illustrating the enlarged view indicators and form no part of the claimed design.
